UNITED STATES PATENT OFFICE.

DAVID KAPLAN, OF BROOKLYN, NEW YORK.

DESIGN FOR A WALL BRACKET FOR LIGHTING FIXTURES.

Application filed August 22, 1924. Serial No. 10,520. Term of patent 3½ years.

To all whom it may concern:

Be it known that I, DAVID KAPLAN, a citizen of the United States, residing at 856 Stone Avenue, Brooklyn, New York, in the county of Kings and State of New York, have invented a new and original and ornamental Design for Wall Brackets for Lighting Fixtures, of which the following is a specification, reference being had to the accompanying drawing, forming part thereof.

Figure 1 is a front elevation showing my new design, and Figure 2 is a plan view of the same.

I claim:

The ornamental design for a wall bracket for lighting fixtures, as shown.

DAVID KAPLAN.
